CHILD'S TOILET SEAT SUPPORT BRACKET ASSEMBLY

Leo M. Gould, Merrill, Wis.

Application February 3, 1956, Serial No. 563,336

4 Claims. (Cl. 4—239)

This invention relates generally to seats for toilet bowls and is more particularly concerned with a novel child's toilet seat support bracket assembly whereby the child's toilet seat is readily disposed in a proper relief position, and may be available in an accessible position adjacent a toilet stool which it cooperates.

At present advised, conventional child's toilet seats when mounted on a conventional toilet stool in some cases prevent closing of the toilet seat and cover, mounting the child's toilet seat on the seat results in marring the finish on the toilet seat and cover, as well as being awkward to handle, at times being stowed on the floor of a bathroom providing an unsightly appearance, and generally providing a constant source of irritation to the parents, nurses, etc. of the child using the same.

A primary object of invention is to provide a novel child's toilet seat combination including a novel child's toilet seat support bracket assembly overcoming the shortcomings of the prior art, encompassing all the beneficial features thereof, and including attended desirable features of storage in an accessible position for ready disposal in a relief position on a toilet stool with which it cooperates.

A further object of invention in conformance with that set forth is to provide a novel child's toilet seat support bracket assembly usable with different conventional child's toilet seats.

Another object of invention in conformance with that set forth is to provide a novel child's toilet seat support bracket assembly including a support member securable on a toilet bowl, a horizontally reciprocable and pivotal support strap element on said support member wherein the support strap element includes transverse hinge means pivotally carrying thereon a hinge assembly wherein the hinge assembly is pivotal to have a leaf portion thereof overlying the support strap element when the child's toilet seat is disposed in a relief position and further permitting the child's toilet seat to be stowed or hung in a readily accessible position adjacent the rear side portion of a toilet bowl upon which the assembly is mounted.

A still further object of invention in conformance with that set forth is to provide a child's toilet seat in combination with a novel support bracket assembly which is readily and economically manufactured, easily installed, used, and maintained, and practical, serviceable and utilitarian for the purpose intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary side elevational view of a toilet stool including a pivoted toilet seat and cover, showing the novel child's toilet seat support bracket assembly mounted thereon, with the child's toilet seat being disposed in a relief position;

Figure 2 is a sectional view taken substantially on line 2—2 of Figure 1, showing in phantom lines the position of the child's toilet seat when stowed and not in use;

Figure 3 is an enlarged perspective view of the novel child's toilet seat support bracket assembly disposed in the position assumed when the child's toilet seat is in the relief position shown in Figure 1;

Figure 4 is an enlarged perspective view similar to Figure 3, showing the relative position assumed by the

2

parts when the child's toilet seat is stowed adjacent a toilet stool upon which the support bracket assembly is mounted; and

Figure 5 is a fragmentary side elevational view similar to Figure 1, showing the child's toilet seat and novel support bracket assembly in the position assumed when the child's toilet seat is stowed in a readily accessible position adjacent the toilet stool.

Referring to the drawings in detail, a fragmentary portion of a toilet stool is indicated generally at 10 including the conventional porcelain stool 12 having a rear flange portion 14 through which extends a hinge assembly 16 for hingedly supporting a conventional toilet seat 18 and cover 20, the hinge assembly 16 generally incorporating a pair of transversely spaced hinge support bolts 22 and 24 extending through suitable vertical aperture portions in the flange 14 of the toilet bowl.

The novel child's toilet seat support bracket assembly is indicated generally at 26, said assembly including a support member 28 comprising a plate element of any suitable character and material, having extending into its rear edge portion 30 a pair of spaced notch or groove portions 32, 34 extending therethrough. The support member 28 has extending vertically from the upper surface portion 36 thereof an integral pivot or mounting pin 38 which slidably and reciprocably receives an elongated strap element 40 which includes a longitudinally extending transverse slot portion 42 disposed on the previously mentioned pivot pin element 38. Considering Figures 3 and 4, it will thus be observed that the support strap element 40 may be moved or reciprocated in a horizontal plane within the limits of the slot portion 42 and pivoted to a laterally disposed position as seen in Figure 4. The support strap element 40 will be of a sufficient length to permit an end portion of the same to extend over the side end portions 44 and 46 of the support member 28, and also extend beyond an underlying side portion of the toilet stool 12.

The support member 28 will be mounted on the toilet stool 12 in overlying relationship relative to the flange portion 14 thereof, by means of the previously mentioned notches 32 and 34 of said support member, being disposed beneath the conventional bolt-shoulders 48 normally found on the mounting bolt portions 22 and 24 of the hinge assembly 16. The aforementioned means i. e. notches 32 and 34 permit the incorporation or the mounting of the support member 28 on a conventional toilet stool; however, other suitable means (not shown) may be utilized on other types of toilet stools.

The support strap 40 includes on its end portion 50 transversely extending hinge means 52 extending transversely across said end portion 50, and rotatably supporting one hinge leaf 54 of a mounting hinge assembly indicated generally at 56. The hinge assembly 56 incorporates a second hinge leaf portion 58 transversely pivoted by hinge means 60 to the hinge leaf 54, and has extending transversely therethrough a plurality of suitable screw apertures 62 receiving therethrough suitable securing screws for mounting the child's toilet seat support bracket assembly on a conventional child's toilet seat indicated generally at 64. The child's toilet seat 64 may conveniently include a rearwardly extending medial portion 66 upon which the hinge leaf 58 may be suitably secured as previously mentioned.

The child's toilet seat 64 includes the conventional seat portion 68 having a suitable back rest 70 thereon and may include suitable oppositely disposed bracket elements secured on a lower surface portion thereof in any suitable manner, said bracket elements being identified at 72 and including a laterally extending portion 74 engageable on the upper surface of the toilet bowl and the depending portion 76 disposed within the toilet

bowl 12 and preventing accidental lateral shifting of the toilet seat 68 about the pivot pin 38 of the novel assembly.

Observing Figures 1, 2 and 3, when the child's toilet seat is to be disposed in a position of use or a relief position, the hinge leaf portion 54 will be pivoted into overlying relationship relative to the upper surface of the strap support element 40 and the seat 68 will be suitably supported on a forward underlying portion of the toilet stool 12. Thus the hinge means 52 and the hinge assembly 56 provides an articulated joint permitting vertical pivotal movement of the cooperating hinged parts. After the child's toilet seat has been used, the same may be raised away from the toilet stool 12 by virtue of the previously mentioned hinge connections, and the support strap 40 being pivoted about the pivot pin element 38, see Figure 4, the child's seat and support strap may be swung to the side of the stool, where, by means of the slot 42 the child's seat may be extended beyond the side of the stool after which the child's toilet seat may be disposed in a hung or depending relationship relative to the toilet stool as clearly seen in Figure 5. When it is desired again to use the child's toilet seat, the seat portion 68 is pivoted vertically by virtue of the previously mentioned hinge connections and disposed once again into the overlying or relief relationship shown in Figure 1 relative to the toilet stool 12.

Thus there has been disclosed a child's toilet seat combination in conjunction with a novel child's toilet seat support bracket assembly which fully conforms with the objects of invention heretofore set forth.

Although one type of child's toilet seat has been disclosed herein, the novel support bracket assembly is readily usable with other types of child's toilet seats.

Various positional directional terms such as "forward," "upper," etc. are utilized herein to have only a relative connotation to aid in describing the device and it is not intended to require any particular orientation with respect to any external elements.

The foregoing is considered as illustrative of the principles of the invention. Further, since numerous modifications and changes will readily occur to those skilled in the art, it is not desired to limit the invention to the exact description and operation shown and described, and accordingly all suitable modifications and equivalents may be resorted to, falling within the scope of the appended claims.

What is claimed is:

1. A child's toilet seat support bracket assembly for use with a toilet stool, comprising a support member, means on the support member for mounting the support member on the toilet stool, an elongated support strap element including means on one end portion thereof permitting pivotal and reciprocable movement of the strap element on the support member, hinge means on the other end portion of the support strap defining a transverse pivot axis portion, and a mounting hinge assembly including a pair of hinge leaf portions pivotally connected by a transverse hinge portion, one hinge leaf portion being pivotally connected to the hinge means on the support strap element, the other of which including means thereon for attachment to a child's toilet seat, the hinge assembly and hinge means defining an articulated joint permitting vertical pivotal movement of the one hinge leaf portion into overlying relationship relative to the support strap disposing the child's toilet seat in a relief position over the toilet stool, and further permitting the child's toilet seat to be hung in depending relationship adjacent the toilet stool.

2. A child's toilet seat support bracket assembly for use with a toilet stool, comprising a support member, means on the support member for mounting the support member on the toilet stool, an elongated support strap element including means on one end portion thereof permitting pivotal and reciprocable movement of the strap element on the support member, hinge means on the

other end portion of the support strap defining a transverse pivot axis portion, and a mounting hinge assembly including a pair of hinge leaf portions pivotally connected by a transverse hinge portion, one hinge leaf portion being pivotally connected to the hinge means on the support strap element, the other of which including means thereon for attachment to a child's toilet seat, the hinge assembly and hinge means defining an articulated joint permitting vertical pivotal movement of the one hinge leaf portion into overlying relationship relative to the support strap disposing the child's toilet seat in a relief position over the toilet stool, and further permitting the child's toilet seat to be hung in depending relationship adjacent the toilet stool, the means on the support member permitting horizontal and pivotal movement including an integral vertical pivot pin element on the support member, the support strap element including an elongated longitudinally extending slot portion journaled on said pivot pin element.

3. In combination, for use on a toilet stool, a child's toilet seat and toilet seat support bracket assembly, said support bracket assembly including a support member, means on said support member for mounting the support member on the toilet stool, an elongated support strap element including means on one end portion thereof permitting pivotal and reciprocable movement of the support strap element on the support member, hinge means on the other end portion of the support strap defining a transverse pivot axis portion, and a mounting hinge assembly including a pair of hinge leaf portions pivotally connected by a transverse hinge portion, one hinge leaf portion being pivotally connected to the hinge means on the support strap element, the other of which including means thereon attaching said hinge leaf to the child's toilet seat, the hinge assembly and hinge means defining an articulated joint permitting vertical pivotal movement of the one hinge leaf portion into overlying relationship relative to the support strap element disposing the child's toilet seat in a relief position over the toilet stool, and permitting the child's toilet seat to be hung in depending relationship adjacent the toilet stool.

4. In combination, for use on a toilet stool, a child's toilet seat and toilet seat support bracket assembly, said support bracket assembly including a support member, means on said support member for mounting the support member on the toilet stool, an elongated support strap element including means on one end portion thereof permitting pivotal and reciprocable movement of the support strap element on the support member, hinge means on the other end portion of the support strap defining a transverse pivot axis portion, and a mounting hinge assembly including a pair of hinge leaf portions pivotally connected by a transverse hinge portion, one hinge leaf portion being pivotally connected to the hinge means on the support strap element, the other of which including means thereon attaching said hinge leaf to the child's toilet seat, the hinge assembly and hinge means defining an articulated joint permitting vertical pivotal movement of the one hinge leaf portion into overlying relationship relative to the support strap element disposing the child's toilet seat in a relief position over the toilet stool, and permitting the child's toilet seat to be hung in depending relationship adjacent the toilet stool, the means on the support member permitting reciprocable and pivotal movement including an integral vertical pivot pin element, said support strap element including an elongated longitudinally extending slot portion journaled on said pivot pin element.
